DRAFTING MACHINE

Ray L. Gentry, Anderson, Ind.

Application October 14, 1954, Serial No. 462,305

2 Claims. (Cl. 33—79)

This invention relates to a drafting machine of the type in which a scale or straight-edge is adjustably carried by an articulated arm for parallel movement over a drafting table, that is, for movement in which the straight-edge is always in a constant orientation about a movable axis extending normal to the surface of the drafting table.

It is an object of my invention to provide in such a machine an improved means for adjusting the scale carrier with respect to the arm, by which the angularity or orientation of the scale may be simply and easily adjusted.

In carrying out my invention in a preferred embodiment, the articulated arm may comprise a pair of jointed links or struts extending from a fixed support to a remote pulley whose axis may be considered as the orientation axis, with belts and pulleys which maintain the remote pulley in a constant orientation about that axis. The remote pulley carries a calibrated index plate, in fixed relation thereto. A scale carrier is fixed to the lower end of a sleeve or hollow shaft which passes concentrically upward through the oriented pulley and is provided at its upper end with a control handle by which the scale-carrier can be adjusted angularly with respect to the index plate. A plunger is slidably received within the sleeve and normally protrudes through the handle for actuation by the palm of the hand. The plunger provides a lock actuator for an index lock which locks the scale-carrier to the index plate in selected angular positions. The handle and plunger provide one-hand control. To change or set the angularity of the scale, the operator grasps the handle with one hand, depresses the plunger with the palm of the same hand to release the lock, and then rotates the handle to swing the scale carrier to the selected position of angularity. He then releases the plunger to lock the scale in its new position of orientation.

These and other features and objects of my invention will appear from the illustrative embodiment of my invention shown in the accompanying drawings. In such drawings:

Fig. 1 is a plan view of a drafting machine embodying the invention, shown mounted on a drafting board; Figs. 2 and 3 are sections taken on the lines 2—2 and 3—3 respectively of Fig. 1;

Fig. 4 is a section through the scale-carrying head of the machine shown in Fig. 1; and

Fig. 5 is a bottom plan view of the scale-carrying head and scale-carrier.

The machine shown in the drawing comprises an articulated arm of the strut and belt type, which is clamped to a drafting board 10 by a clamp 11. The upper end of the clamp forms a fixed pulley 18 provided with a belt groove 19 in its outer circumferential surface. The arm comprises an inner strut 12 and an outer strut 14. The inner strut 12 is carried by a head 13 which has a central boss received within a set of needle bearings 22 so that the strut 12 will freely pivot about the axis of

2

the fixed pulley 18. At their adjoining ends, the struts 12 and 14 are jointed to each other on an axis which is normally parallel to the axis of the fixed pulley 18. To this end, the two struts are provided with heads which have coaxial central cylindrical bosses 20 and 21, and these carry the inner races of two sets of needle bearings within the hub of an intermediate pulley 26. A bolt 15 secures the two heads in place for frictional pivotal movement relative to each other, and the pulley 26 is freely rotatable with respect to the struts 12 and 14. The outer end of the outer strut 14 carries a head 40 which forms a central depending boss to support the inner race of a set of needle bearings on which a pulley 16 is journaled.

A belt 28 is engaged in the belt groove of the fixed pulley 18 and with a belt groove at the top of an intermediate pulley 26. A second belt 34 is engaged in a belt groove at the bottom of the intermediate pulley 26 and in a belt groove in the remote pulley 16. The belts maintain the three pulleys in a constant orientation with respect to each other, and thus maintain the remote pulley 16 in a fixed orientation, the same as that of the fixed pulley 18. Conveniently, the struts 12 and 14 are adjustable in length, to maintain a suitable tension on the belts 28 and 34.

The articulated arm structure described above is of a known type, and other types of articulated arms might be used. The present invention is primarily concerned with the scale-carrying head at the free end of the articulated arm and with its adjustment. The structure of such head is best shown in Fig. 4.

As shown in Fig. 4, the constant-orientation pulley 16 carries a bottom plate 42 on which is mounted a fixed index plate 44. The hub of the pulley 16 and the central boss 38 of the head 40 form a cylindrical opening to receive a concentric sleeve or hollow shaft 46. The lower end of the sleeve 46 is provided with a flange 47 to which is secured a scale carrier 48 for the desired scales or straight-edges 49. The upper end of the sleeve 46 carries a handle 50 by which the scale carrier 48 may be rotated about the axis of the constant-orientation pulley 16 to vary its angular position with respect to the index plate 44.

To lock the scale carrier 48 in selected positions of angular adjustment, the index supporting plate 42 is provided with a series of holes 52 at suitable angular positions about the constant-orientation axis of the pulley 16. Conveniently, the angular spacing between the holes is 15°. A pin 54 carried on a tongue 58 mounted on the scale carrier 48 is arranged to engage upwardly into the holes 52. As shown in Fig. 5, the scale carrier 48 is provided with a slot 56 extending radially from the axis of the sleeve 46. A tongue 58 is mounted in this slot 56 and is hinged to the scale carrier 48 by a leaf spring 60, which not only provides for pivotal movement of the tongue 58, but biases that tongue upward. The lock pin 54 is carried by the tongue 58 in a position to enter the index holes 52 from below.

Engagement and release of the pin 54 on the tongue 58 is controlled by a plunger 62 slidably mounted in the central sleeve 46. The upper end of the plunger carries a flanged button 64 which normally stands above the top of the handle 50, and through which the plunger 62 is spring pressed upwardly by a spring 66. The lower end of the plunger 62 is provided with an annular notch 68, conveniently formed between the bottom surface of the plunger 62 and the head of a screw 63. The free end of the tongue spring 60 is notched and received in the annular notch 68 of the plunger 62, and the upward bias on the plunger 62 urges the tongue 58 upward to engage its pin 54 in an aligned index hole 52.

The bottom of the scale-carrying head is desirably pro-

vided with a cup-shaped shoe 70, to support the head on the surface of the drafting table 10 and to provide clearance for movements of the plunger 62. A slot in the wall of the shoe provides clearance for pivotal movement of the tongue 58.

The drafting machine shown is extremely simple and convenient to use and to adjust. In preparing it for use, the struts and belts and pulleys of the articulated arm are adjusted to provide the desired orientation of the pulley 16 and the index plate or protractor 44 which it carries. Normally, the scale carrier 48 is calibrated to orient its scales or straight-edges parallel with the edges of the drafting table 10, the scales may then be moved freely over the drafting table 10 and will be maintained in that same orientation by the action of the articulated arm and its belts. When it is desired to adjust the scales to some different angular position, the draftsman simply grasps the handle 50 with one hand, depresses the button 64 to release the scale carrier, and rotates the handle 50 as desired to swing the scales to the desired position. The depression of the button 64 depresses the plunger 62, which moves the free end of the tongue 58 downwardly, causing that tongue to pivot substantially about its outer end and to lower the pin 54 out of engagement with the aligned index hole 52. With that pin disengaged, the scale carrier is freely rotatable to a new position. If the desired new position is one for which an index hole 52 is provided, that is, if it is say 15° from the original position, the scale carrier will be guided to the new position and locked in that new position by engagement of the pin 54 in the appropriate hole 52. To permit and cause that engagement, the operator simply releases the pressure on the central button 64 within the handle 50. For intermediate positions, at which no index holes 52 are provided, the pin 54 simply engages the flat bottom surface of the index-carrying plate 42. If it is desired to lock the scale carrier 48 in such intermediate positions to adjustment, it may be provided with a clamp nut 72 to clamp the edge of the index plate 44 to the scale carrier 60.

I claim as my invention:

1. In a drafting machine in which a scale support is maintained in constant orientation about a laterally mov-

able axis, a hollow scale carrier shaft journalled through said support and angularly adjustable with respect thereto by rotation on said axis, a scale-carrier fixed to said shaft below said support and angularly adjustable therewith, an adjustment handle fixed on the upper end of said shaft, a radially extending index plate carried by said support and having a plurality of axially extending index holes at angularly spaced points about said axis, a lock-pin member extending radially below said index plate and carrying an upstanding lock-pin for selective reception in the index holes in said index plate, a leaf spring connection between said lock-pin member and said scale carrier and accurately fixing the position of said lock-pin in the plane of said scale carrier, the flexure of said spring permitting hinged movement of said lock-pin member to carry said lock-pin in a generally axial direction into and out of said index holes, and an index release plunger axially movable in said hollow scale-carrier shaft and operatively connected at its lower end to the lock-pin member to actuate the same for releasing the lock-pin from the index holes, the top end of said plunger extending through and above said adjustment handle by which said scale-carrier shaft is rotatably adjusted in said support, in position to be engaged and depressed by the palm of the hand which grasps the handle to release the lock-pin and permit the scale to be adjusted by rotation of the handle.

2. Drafting machine apparatus according to claim 1, in which the plunger is axially connected to the lock-pin member, with the addition of a spring between the plunger and the handle cooperating with the leaf-spring connection to bias the lock-pin to locking position.
